UNITED STATES PATENT OFFICE.

FERDINAND F. UNCKRICH, OF SANDUSKY, OHIO, ASSIGNOR TO WALTER H. STONE, OF SAME PLACE.

NUT-LOCK.

SPECIFICATION forming part of Letters Patent No. 453,222, dated June 2, 1891.

Application filed March 31, 1888. Serial No. 269,155. (No model.)

To all whom it may concern:

Be it known that I, FERDINAND F. UNCKRICH, a citizen of the United States, residing at Sandusky, Erie county, Ohio, have invented new and useful Improvements in Nut-Locks, of which the following is a specification.

My invention relates to nut-locks, its object being to produce a cheap, practicable, and efficient holding device to prevent loosening of the nut; to which end it consists in the combination, with the nut and a holding-washer, of a catch of peculiar construction, adapted when in place to lie wholly within the exposed faces of the nut, so constructed and arranged as to insure its perfect automatic holding action and at the same time permit its ready disengagement when desired, all as more fully hereinafter set forth.

My invention is illustrated in the accompanying drawings, in which—

Figure 1 is a general side view of the nut and washer, sectioned in parts to show details of construction; Fig. 2, a general plan view of same; Fig. 3, a general side view of a rail-joint and fish-plate, showing the application of the washer thereto; Fig. 4, a detached view of the plunger or catch; and Fig. 5, a detached sectional view of the nut, showing the construction of the plunger-aperture and the surface guide-recess for the head of the plunger-stem.

Referring now to the drawings in aid of the description, A designates the nut, and B a holding-washer. The washer is provided with radial grooves or recesses b or their equivalent, and with a tongue or tongues to embed in wood, or other means of preventing rotation, according to the circumstances of use, such as a straight edge at one side to bear against a flange or abutment upon the fish-plate, used in rail-joints, as in Fig. 3.

The holding-catch a is a plunger seated in a counterbored aperture c in the nut and held outward by a spring s, coiled about the stem of the plunger within the counterbore of the nut. The lower face of the catch a is beveled to ride freely over the ridges between the radial grooves of the washer (as permitted by the compression of the spring s) in one direction, but present a vertical resisting face

against movement in the opposite direction. The stem a' of the plunger extends upward in a smaller perforation through the nut.

As a guide to insure the proper relation of 55 the beveled face of the catch to the recesses of the washer, the upward projection of the stem a' is bent over laterally, and when the catch is in its lowest or engaging position seats in a correspondingly elongated depression c' in the upper face of the nut. As the bent stem a' can enter the depression only in one position, it forms a guide for the engaging bevel-face of the catch, which can thus present its bevel-face to the washer only in 60 proper relation to the holding depressions. The bent stem a' also possesses another function of great convenience, to wit: When it is desired to release the nut, the plunger is lifted by inserting the edge of any sharp instrument beneath the bent stem a' and the plunger lifted within the counterbored aperture of the nut against the resiliency of its 65 spring s. At the limit of its upward lift the bent stem a' is turned around, over, and is held upon the face of the nut out of its depression c', thus retaining the catch elevated and out of engagement.

It will be seen that when the catch a is seated and engaged with the washer its bent 80 stem is wholly within the depression c', and thus no part is left projecting, but all is contained within the exposed faces of the nut and cannot be injured in any way, nor interfere with the use of the wrench. The catch 85 being in proper position for action it rides over the ratchet-face of the washer as the nut is turned and automatically seats itself to prevent backward rotation of the nut.

It will be obvious that instead of a "ratch- 90 et-face" the washer may be provided with a concentric series of "pits" or holes to receive the end of the plunger, and that the latter need not be beveled. In such case the guid- 95 ing function of the bent stem will not be re- alized, but its convenience in the other re- spects enumerated will not be impaired.

I claim as my invention and desire to secure by Letters Patent of the United States—

The improved self-locking nut-lock em- 100 bodying a ratchet-faced holding-washer, a nut provided with a counterbored perforation ad-

1
jacent to its bolt-aperture, said perforation
extended by a lateral recess in the outer face
of the nut, and a spring-impelled bevel-faced
plunger-catch seated in said perforation, hav-
5 ing its stem extended laterally in said recess,
wholly within the outer face of the nut, said
recess serving also as a guide to preserve the
engaging face of the plunger-catch in proper
relation with the bevel-faces of the washer to
10 permit the nut to be tightened, but prevent

its opposite movement, substantially as set
forth.

In testimony whereof I have hereunto set
my hand in the presence of two subscribing
witnesses.

FERDINAND F. UNCKRICH.
